UNITED STATES PATENT OFFICE.

WILLIAM F. BARRY, OF WOONSOCKET, RHODE ISLAND, ASSIGNOR OF ONE-HALF TO WILLIAM B. LINCOLN, OF SAME PLACE.

POWDER-INSUFFLATOR.

SPECIFICATION forming part of Letters Patent No. 660,042, dated October 16, 1900.

Application filed July 12, 1900. Serial No. 23,402. (No model.)

To all whom it may concern:

Be it known that I, WILLIAM F. BARRY, a citizen of the United States, residing at Woonsocket, in the county of Providence and State of Rhode Island, have invented new and useful Improvements in Powder-Insufflators, of which the following is a specification.

My invention relates to improvements in that class of powder insufflators or injectors which comprise a receptacle or reservoir for powder, an elastic bulb connected with one end of said receptacle or reservoir, and a nozzle connected with the other end thereof.

It consists in a certain peculiar construction the novelty and advantages of which will be fully understood from the following description and claims when taken in conjunction with the accompanying drawings, in which—

20. Figure 1 is a plan view of an injector constructed in accordance with my invention. Fig. 2 is a longitudinal central section of the same. Fig. 3 is a transverse section taken in the plane indicated by the broken line 3-3 of Fig. 1 and illustrating the rotatable band in the position it is caused to assume in order to close the powder chamber or reservoir.

In the said drawings similar letters designate corresponding parts in all of the views, 30 referring to which—

A is the body, B the elastic bulb, and C the nozzle, of my improved device.

The body A is preferably made in one piece of brass or other suitable metal, and comprises an intermediate diametrically-enlarged portion *a*, in which is formed a chamber or reservoir *b*, and tubular portions *c* *d*, which communicate with and extend in opposite directions from said chamber or reservoir, as shown. The intermediate portion *a* is exteriorly of circular form in cross-section and is provided at an intermediate point of its length with a filling-aperture *e* and at its ends with flanges *e'*. The tubular portion *c* is interiorly threaded at its outer end to receive a threaded nipple *f* on the bulb *B*, while the outer end of the tubular portion *d* is slightly enlarged, as indicated by *g*, to receive one end of a rubber tube *D*. Such end of the rubber tube is secured by cement in the enlargement *g*, while its opposite end is inter-

posed between and secured by cement to one end of the nozzle *C* and a metallic annulus *h* thereon.

The nozzle *C* is preferably made of glass to adapt it to be readily cleansed and is shaped as shown and flexibly connected to the body through the medium of the rubber tube, so as to permit of its being readily inserted in the nasal passages and other passages and cavities of the body.

E is a rotatable band which is mounted on the intermediate enlarged portion *a* of the body, between the flanges *e'* thereof, and snugly fits the same. This band is provided with an aperture *i*, adapted to register with the aperture *e* of the body portion *a*, and is also provided with the milled or roughened end portions *j* to permit of its being readily rotated.

It will be readily appreciated from the foregoing that when the band *E* is rotated until its aperture *j* is coincident with the aperture *e* of the body access is afforded to the chamber or reservoir *b*, and said chamber or reservoir may be conveniently filled with powder, while when said band is rotated to carry its aperture away from the aperture *e* the said aperture *e* is tightly closed and the escape of powder through the same precluded. It will also be appreciated that the band *E* may be quickly and easily turned to open or close the chamber or reservoir *b*, and yet is not liable to be casually turned incident to the use of the injector.

My improved injector is used in the usual manner—that is to say, the nozzle *C* is inserted in the nasal or other passage or cavity to be treated and the bulb *B* is compressed one or more times to force the powder into such passage or cavity.

I have entered into a specific description of the construction and relative arrangement of the parts embodied in this the preferred embodiment of my invention in order to impart a full, clear, and exact understanding of the same. I do not desire, however, to be understood as confining myself to such specific construction and arrangement of parts, as such changes or modifications may be made in practice as fairly fall within the scope of my claim.

Having described my invention, what I claim, and desire to secure by Letters Patent, is—

In the injector or insufflator described, the body formed in one piece and comprising the intermediate, diametrically-enlarged portion having the chamber formed therein, and also having the filling-aperture in the wall of the chamber, and the exterior flanges e' , and the tubular portions communicating with opposite ends of the chamber, the rotatable band mounted on and snugly fitting the body between the flanges e' thereof and having an aperture adapted to coincide with the aper-

ture in the wall of the chamber or reservoir, 15 and also having the roughened end portions, the elastic bulb connected to one tubular portion of the body, the nozzle, and the rubber tube interposed between and connected to the other tubular portion of the body and the nozzle, substantially as specified.

In testimony whereof I have hereunto set my hand in presence of two subscribing witnesses.

WILLIAM F. BARRY.
